United States Patent Office.

ANTHONY T. NORGAN, OF PALO ALTO, PENNSYLVANIA.

Letters Patent No. 97,797, dated December 14, 1869; antedated December 7, 1869.

IMPROVEMENT IN DEVICES FOR FASTENING PISTONS TO PISTON-RODS.

The Schedule referred to in these Letters Patent and making part of the same.

To all whom it may concern:

Be it known that I, ANTHONY T. NORGAN, of Palo Alto, in the county of Schuylkill, in the State of Pennsylvania, have invented a new and improved Mode of Fastening Pistons and Cross-Heads to Piston-Rods; and I do hereby declare that the following is a full, clear, and exact description thereof, reference being had to the accompanying drawings, and to the letters of reference marked thereon.

Figure 1 is a view of piston-rod A, having the piston B firmly secured, by the nut C, in its proper position, with a similar nut, D, at the other end, to secure the cross-head.

Figure 2 is a view of piston-rod B, cut at red line, to show the concave cone 2, corresponding to convex cone on nut C.

Figure 3 is an end view of the piston B.

Figure 4 is a view of nut C, complete.

Similar letters indicate corresponding parts in the figures.

The nature of my invention consists in devices for securing piston-rods to cross-heads and pistons, in a cheap and durable manner, and providing an easy method of replacing the same as required, as herein-after described.

To enable others skilled in the art to make and use my invention, I will proceed to describe its construction and operation.

I construct the piston-rod as shown at fig. 1, having the threads at each end, also, with the shoulders 1, for the piston and cross-heads to rest against; the piston B having the hole cored out large enough to allow the end of the rod A to slip into, also having the concave cone 2, figs. 2 and 3, turned out true with

the circumference of the piston; the nut C, fig. 4, being constructed with the convex cone to fit into the corresponding conical recess in piston B; the nut C, with cone, being turned up perfectly true on the piston-rod A, adjusts the piston B in its proper position.

The operation is as follows:

The rod A, piston B, and nut C being made as described, the rod is put into the piston, and the nut put on and screwed up, the convex part of the nut goes into the concave part of the piston B, and combines the whole properly and solidly together.

The same mode secures the cross-head to the other end of the rod, and, by using two nuts at either end, one reverse to the other, would allow the cross-head or piston to be adjusted to the exact length desired.

The advantages of this mode of constructing the pistons and piston-rod entirely dispenses with the turning and the fitting of the rod into pistons and cross-heads, as the holes in them are cored out larger than the rod; also, dispensing with the key-holes and keys, allowing the cross-heads and pistons to be easily removed and others put on, as may be required, by breakage or other causes.

Having thus fully described my invention, What I claim as new, and desire to secure by Letters Patent, is—

The construction and arrangement of the piston-rod A with convex nut C and piston B, substantially as described.

A. T. NORGAN.
